UNITED STATES PATENT OFFICE.

EDWARD A. HILL, OF NORWALK, OHIO.

HEATING ATTACHMENT FOR FEED-WATER INJECTORS.

1,221,989.

Specification of Letters Patent.

Patented Apr. 10, 1917.

Application filed December 6, 1915. Serial No. 65,316.

To all whom it may concern:

Be it known that I, EDWARD A. HILL, a citizen of the United States, residing at Norwalk, in the county of Huron and State of Ohio, have invented certain new and useful Improvements in Heating Attachments for Feed-Water Injectors; and I do declare the following to be a full, clear, and exact description of the invention, such as will enable others skilled in the art to which it appertains to make and use the same.

This invention contemplates certain new and useful improvements in feed water heaters particularly designed for use with locomotives, but capable of use in other connections as will be understood.

One object of the invention is to provide simple and efficient means for attachment to a feed water injector of a steam boiler and controllable so that the feed water may be supplied to the boiler at a low temperature, such as may be desirable in cooling down the boiler, at a comparatively high temperature when the engine is standing or drifting, and at a very high temperature when the engine is working so that a very small amount of contraction will occur in the heating surfaces when the water comes in contact with them.

Another object is to provide a device of this character which may be readily applied to any injector already in use.

With these and other objects in view, the invention consists of certain novel features of construction, combination and arrangement of parts as will be hereinafter more fully described and claimed.

In the accompanying drawings:

Figure 1 represents a side elevation of a portion of a locomotive showing this improved attachment applied;

Fig. 2 is an enlarged side elevation of an injector with this improved attachment applied and shown particularly in section.

In the embodiment illustrated this improved attachment is shown applied to a feed water injector of the type known on the market as the "Ohio" injector and in which the usual water supply pipe W is shown designed to be connected with a suitable source (not shown) and which leads to the combining tube (not shown) and contained in the casing C, the flow of water being controlled by the usual valve V. The steam is supplied to the receiving tube (not

shown) within the casing C from the pipe P in the usual manner, the supply of steam being controlled by a lever L connected with a valve within the casing. The usual overflow nozzle N is shown connected with the casing C and a valve v is provided for controlling air to the overflow chamber such as is usual in injectors of this character. The delivery tube D of the injector is shown at the right of Fig. 2 discharging opposite the check valve c v, the stem of which is guided in the usual manner in a guide g and through which the feed water from the injector is discharged usually directly into the boiler feed water pipe.

The attachment constituting this invention is shown applied to the outer or free end of the injector which is screw threaded as shown at s to provide for its connection with the feed water pipe of a boiler. This attachment comprises a casing 1 having outwardly bulged side walls 2 merging at their opposite ends into reduced necks 3 and 4, the neck 3 being internally threaded for connection with the threads s of the injector, and the neck 4 externally threaded to adapt it for connection with a feed water tube of the boiler, said neck being inserted in the tube in a manner similar to that in which the injector is usually connected by the threaded end s thereof.

A tapered nozzle 5 has its outer end formed integral with the casing 1 at the rear end thereof adjacent the base of the neck 3, the larger end of said nozzle being substantially of the same width as said neck. This nozzle extends longitudinally through the casing 1 with its tapered front end disposed adjacent the front end of the neck 4 being here shown disposed slightly within said neck. By so forming this nozzle and bulging the walls 2 of the casing 1, a steam space or chamber 6 of considerable size is formed within the casing around the nozzle and the tapered walls of the nozzle serve as guides for directing the steam toward the discharge end of the casing, said steam being admitted through an opening 7 formed in the side wall of the casing adjacent the connected end of the nozzle so that the steam entering through this opening impinges against the opposed wall of the nozzle and is directed outwardly thereby toward the discharge end of the casing in the same direction as the stream of outflowing

water and commingles at the outer end of the casing with the water entering said casing through the small end of the nozzle 5 and whereby the steam and water are thoroughly commingled and the water heated by the contact of the live steam, a portion of the steam being converted into water and passing with the water into the feed water tubes of the boiler. By making the nozzle integral with the casing said nozzle cannot work loose and the alinement or adjustment thereof be changed.

10 A steam supply pipe 8 communicates with the opening 7 and is provided with an externally threaded collar 7' against the outer end of which the end of a tubular neck 8' carried by the casting 2 abuts and is connected thereto by a suitable sleeve 10 having a fluid tight connection therewith.

20 This steam supply pipe 8, which for convenience in description will be termed the main supply pipe, is shown L-shaped or right angular in formation with the longer arm 11 thereof externally threaded at its rear end and connected with a pipe coupling 12 through an opening in one side wall thereof, said coupling 12 being engaged at one end with the pipe P and at its other end with a pipe P' which leads to the steam 25 space of the boiler and through which steam is supplied both to the pipe P and to the pipe 8 which connects with the heater casing 1. The coupling 12 and the arm 11 of pipe 8 form a T-shaped connection.

30 An auxiliary steam pipe 13 is connected with the long horizontally disposed arm 11 of the pipe 8, a three-way valve 14 being arranged at the connection of said auxiliary pipe 13 with the main pipe 8 and said valve 40 is provided with the usual handle 15 for actuating it. This pipe 13 leads to a steam pipe 16 on the engine which is connected with a superheater unit, not shown and is 45 designed for supplying superheated steam to the heater casing 1 when the engine is working as will be hereinafter more fully described. A check valve 17 is arranged in the pipe 13 being here shown disposed adjacent its connection with the pipe 8 although obviously it may be disposed at any 50 other desired point.

55 As shown the pipe 8 is composed of a plurality of sections connected by suitable couplings, an elbow coupling 18 being here shown connecting the short arm of the pipe with a section 19 of the long arm thereof and the three-way valve 14 is shown mounted in a T-shaped coupling 20 arranged intermediately the ends of the long arm 11 60 and with the head 21 thereof connected at its opposite ends with sections 22 and 23 of said long arm 11, the section 22 being connected at one end with said head 21 and at its other end with the coupling 12 and constitutes the shank of the T formed in con-

nection therewith, while the section 23 is connected at one end with the other head of the T-shaped coupling 20 and at its other end with the section 19. This section 19 is provided with an angular wrench receiving 70 collar 24 as are also the ends of the head 21, to provide for the connection and disconnection of the sections. This pipe 8 is made in sections so that the length thereof may be varied to adapt the attachment to 75 be applied to injectors of different sizes and in which the delivery end and the steam supply pipe are disposed at varying distances apart.

80 A pet cock 25 is preferably arranged in the pipe 8 in advance of the three-way valve 14 between said valve and the casing 1 for the purpose of detecting any leakage which might occur in the three-way valve 14.

85 The auxiliary steam pipe 13 is preferably jacketed or otherwise protected to prevent the radiation of heat therefrom which would result in the undesirable condensation of the steam during its passage through said pipe from the pipe 16 to the main pipe 8.

90 In the operation of this device the lever L having been properly positioned to supply water and steam to the delivery tube D in the usual manner when the engine is standing still or drifting, the valve stem 15 is operated to position the three-way valve 14 which it controls into position to bring the rear end or section 22 of the pipe 8 into communication with the steam pipe P' and with the casing 1, so that steam is fed 100 through said pipe 8 from the pipe P' into the casing and is directed outwardly therefrom by the tapered walls of the nozzle 5 commingling at the outer end of said casing with the water supplied through said nozzle 105 whereby the water is heated to a high temperature before entering the feed water tubes of the boiler.

110 When the engine is working and it is desired to supply the feed water to the boiler at an extremely high temperature so as to provide for the least possible amount of contraction in the heating surfaces against which the water impinges, the valve stem 15 is turned to position the valve 14 so as to 115 cut off the rear section 22 of the main pipe 8 and bring into communication with said pipe 8 the auxiliary steam supply pipe 13 which is connected with the steam pipe 16. When this valve is so disposed the superheated steam from the pipe 16 will be directed through the pipe 13, check valve 17, three-way valve 14 into the pipe section 23 from which it passes into the casing 1 of the heater and commingles with the water admitted into said casing through the nozzle 5, heating said water to an extremely high temperature before it passes from said casing into the feed water tubes of the boiler.

120 125 130 It is desirable that when the engine is

working that the temperature of the feed water be raised to the highest possible point before contacting with the heating surfaces which are at this time subjected to the intense heat of the fire of the engine and the nearer the temperature of the feed water can be brought to the temperature of these heating surfaces before coming in contact therewith, the less contraction of the surfaces will occur when the water comes in contact with them, and hence this arrangement whereby superheated steam is fed to the casing 1 and commingled with the feed water when the engine is working, has been found most effective.

When for any reason it is desired to cool off the boiler, the valve 14 is so positioned as to cut off communication of both the pipe 13 and the main pipe section 22 from the casing 1 and permit the water to enter the feed water tubes directly from the delivery tube D through the nozzle 5 in the usual manner without heating it after it leaves said delivery tube.

From the above description it will thus be obvious that this attachment is operable to supply feed water to the boiler at varying degrees of temperature, simply by shifting the valve 14 into the desired position.

It is however to be understood that as all engines are equipped with injectors, but not all with superheaters the device can be successfully used on any engine not so equipped by merely dispensing with the pipe 13 and check valve 17 and plugging up the connection for pipe 13 on top of the three-way valve.

Copies of this patent may be obtained for five cents each, by addressing the "Commissioner of Patents, Washington, D. C."

I claim as my invention:

In combination with a pipe for connection with a superheater unit of a boiler, of a valve-controlled water supply pipe, a valve-controlled steam supply pipe, an injector arranged between said pipes and having a delivery tube communicating therewith and provided with a check valve arranged in advance of said tube, an auxiliary injector connected at one end with said first mentioned injector in advance of said check valve and adapted to be connected at its other end with the boiler feed water tube, a steam supply pipe connecting said auxiliary injector with said first mentioned steam supply pipe above said first mentioned injector, a superheated steam supply pipe connected with said auxiliary injector connecting pipe and with the pipe for connection with the superheater unit of the boiler and having a check valve therein, and a three way valve located at the junction of said superheated steam supply pipe with the auxiliary injector connecting pipe, whereby said superheated steam supply pipe or said second mentioned injector steam supply pipe may be cut off when desired or both of them, to provide for the supply to the boiler of feed water at three different temperatures.

In testimony whereof I have hereunto set my hand in presence of two subscribing witnesses.

EDWARD A. HILL.
